US00D418118S

United States Patent [19]

Habeshaw et al.

[11] Patent Number: Des. 418,118

[45] Date of Patent: ** Dec. 28, 1999

[54] **ELECTRONIC DEVICE FOR READING ANALYTICAL TESTS**

[75] Inventors: **Rosie L. Habeshaw**, Bedford; **Andreas Mehne**, Cambridge, both of United Kingdom

[73] Assignee: **Unilever Patent Holdings BV**, Vlaardingen, Netherlands

[**] Term: **14 Years**

[21] Appl. No.: **29/093,384**

[22] Filed: **Sep. 9, 1998**

[30] **Foreign Application Priority Data**

Mar. 13, 1998 [GB] United Kingdom 2073191

[51] LOC (6) Cl. **14-02**

[52] U.S. Cl. **D14/107**; D14/100; D10/46

[58] Field of Search D14/100, 105, D14/107, 114; D10/46; D24/107; 361/680-685

[57] **CLAIM**

The ornamental design for an electronic device for reading analytical tests, as shown and described.

DESCRIPTION

FIG. 1 is a top front and side perspective view of an electronic device for reading analytical tests showing our new design;

FIG. 2 is a top rear and opposite side view;

FIG. 3 is a view from below;

FIG. 4 is a right side view;

FIG. 5 is a left side view;

FIG. 6 is a rear view; and,

FIG. 7 is a front view.
